DECORATIVE ORNAMENT FOR A MIRROR OR THE LIKE

Huey T. Keller, High Point, N.C., assignor to Empire
Furniture Corporation, Johnson City, Tenn., a corporation of Virginia

Filed Oct. 18, 1968, Ser. No. 14,054

Term of patent 14 years

Int. Cl. D6—01

U.S. Cl. D33—9

FIG. 1 is an elevational view of a decorative ornament for a mirror or the like, showing my new design;

FIG. 2 is a front perspective of my new design; and

FIG. 3 is a front elevational view of such design.

The back of the mirror ornament is plain and unornamented.

I claim:

The ornamental design for a decorative ornament for a mirror or the like, as shown and described.
